DISPENSING RACK

Richard M. Robbins and Robert V. Robbins,
Loveland, Colo.

Application April 8, 1940, Serial No. 328,502

4 Claims. (Cl. 242—55.4)

This invention relates to improved racks for dispensing roll goods.

There are many instances where roll goods such as foil, Cellophane and paper wrappings, oil cloth, and the like, are to be dispensed in pieces from the rolls as required.

In a flower shop, for instance, various types of ornamental wrappings are usually on hand. Such wrappings commonly are colored foil, Cellophane, paper, or the like, and are used in wrapping cut flowers or potted plants in a color or design to suit the situation. Since a variety of colors and/or designs are usually kept ready for use, it is highly desirable to have the individual rolls of the various materials racked ready for convenient selection. If the individual rolls are scattered about the establishment, they may become difficult to locate and select.

Since these wrappings come in rolls, there is also the problem of cutting or tearing a piece therefrom and if an ordinary knife or scissors are used, the cutting requires some time and may not be entirely neat. Furthermore, an extraneous instrument for cutting easily may be mislaid and annoyance thus occasioned. It is manifestly inefficient simply to tear a piece from the roll, leaving ragged edges and wasting material.

Therefore, it is a principal object of the present invention to provide a combination rack and cutter for a plurality of rolls of material, from which pieces are to be selectively taken.

Another object is to provide such a combination rack and cutter, wherein the cutter may be moved selectively to the desired roll and immediately placed in cutting relationship thereto.

A further object is to provide in such a device, means whereby the rolls are held against accidental or inadvertent rotation which would unroll the material therefrom.

Still another object is to provide such a rack wherein rolls may be selectively mounted or removed.

Other objects and advantages reside in details of design and construction which will be more fully disclosed in the following description and in the drawing wherein like parts have been similarly designated and in which:

Figure 1 is a general front elevation of a combination rack and cutter that is made according to this inventive concept;

Figure 2 is a sectional view taken along the line 2—2 of Figure 1;

Figure 3 is a top plan view of the device shown in Figure 1;

Figure 4 is an enlarged fragmentary sectional

view taken along the line 4—4 of Figure 3 as the device would appear with some of the rolls removed; and

Figure 5 is an enlarged fragmentary sectional view taken along the line 5—5 of Figure 1.

In order to disclose an operative reduction to practice of this inventive concept, reference in detail will be had to the various views in the accompanying drawing. However, since changes in details can be made without departing from the spirit of the invention, the instant example is not to be construed as expressing or implying any limitation to the invention, the scope of which is in reality measured by the appended claims.

In the drawing, reference character 15 denotes a hollow rectangular frame structure as a whole, inclusive of normally vertical side frame members 16 and 17 provided with vertical undercut grooves or ways 18 and 19 respectively. The inner edge of side frame member 16 is provided with a plurality of angular notches 20, and side frame member 17 is provided with correspondingly positioned holes so that a plurality of bars 21 may be removably positioned in said holes and notches to be supported on the frame structure 15.

Rolls 22 of material of the character hereinbefore described are selectively mounted upon the bars 21, where they are visible, rotatable, and conveniently accessible. Where the rolls are mounted on tubes of larger diameter than the bars 21, hollow rollers may be inserted into the ends of the tube with a bar 21 extending through the hollow portion as shown at 40 in Figure 1.

Back of the mounted rolls 22 are a series of U-shaped spring members 23 spaced in two vertical rows, the spring members in one row being in staggered relationship to the spring members in the other row and in a position to bear yieldingly upon the rolls to prevent their accidental or inadvertent rotation. The U-shaped springs in one row are positioned to cross the springs in the other row in substantial horizontal alignment with the bars 21, as indicated at 24 in Figure 4. As a consequence of this particular arrangement of the spring members 23, spring tension is applied to each roll in two directions as at 25 and 26.

T-shaped slides 27 and 28 are slidably carried in the grooves or ways 18 and 19 respectively, and they in turn support a movable cutter element indicated as a whole by reference character 29, and which comprises a cross bar 30 and a cutter blade 31 hingedly attached to said bar 30.

A spring member 32 is positioned on the cross bar 30 to urge the cutter blade 31 away from the rolls 22, but the hinged mounting limits the movement of the cutter away from the rolls to a position wherein it is in substantially vertical alinement with the cross bar 30.

A handle 33 is conveniently provided on the bar 30 whereby it may be selectively moved up and down to bring the cutter blade 31 in alinement with any roll 22 that is selected for use.

Attached to the cutter element 29 is a cord 34 which is reeved over a pulley 35 and connected with a counterweight 36, whereby the weight of the cutter element 29 is substantially balanced so that it may be moved up and down with a minimum of physical effort and it will remain in any selected position.

It is manifest that racks of this character may be made in various sizes to accommodate a plurality of rolls of material, and that such rolls may be readily mounted on or removed from such a rack. When so mounted, the rolls are visible and readily accessible and the cutter element may be moved to bring the cutter blade 31 in alinement with the selected roll, whereupon the hinged cutter blade 31 may be pressed against the tension of the spring 32 to contact the selected roll.

The user grasps the exposed edge of the material on the selected roll and pulls as much of it out past the cutting edge as is desired for use. This unwinding of the material obviously could be done either before or after the cutter blade is positioned. When sufficient material is unrolled and the cutter is in contact with the selected roll, the material may be cut off by quickly and progressively pulling it against the cutting edge across the width of the material.

The cutter blade extends across the full width of the material and it may have a straight cutting edge or a notched cutting edge, as desired. While rolls of uniform length have been illustrated as mounted upon the rack, it is, of course, contemplated that rolls of varying widths of any material within the capacity of any given rack, may be mounted thereon, and dispensed therefrom.

What we claim is:

1. A device of the character disclosed comprising a rack element inclusive of means for rotatably mounting a plurality of rolls of material thereon, a cutter element inclusive of a bar

mounted on the rack for sliding movement past rolls on said rack, a cutter blade hinged to the bar and movable therewith to selected rolls, resilient means on the element for urging the cutter blade away from the rolls, said cutter blade being manually movable against the resilient means to contact a selected roll.

2. A device of the character disclosed comprising a rack element inclusive of means for rotatably mounting a plurality of rolls of material thereon, a cutter element inclusive of a bar mounted on the rack for sliding movement past rolls on said rack, a cutter blade hinged to the bar and movable therewith to selected rolls, resilient means on the cutter element for urging the cutter blade away from the rolls, said cutter blade being manually movable against the resilient means to contact a selected roll, and spring means positioned on the rack to contact rolls of material mounted thereon, whereby said rolls are held against unwanted rotation.

3. A device of the character disclosed comprising a rack element inclusive of means for rotatably mounting a plurality of rolls of material thereon and having parallel undercut ways at opposite sides, slides fitted in the ways, a bar carried on the slides and positioned across the rack adjacent rolls thereon, a cutter blade hinged to said bar for conjoint movement therewith, and resilient means on the bar positioned to urge the cutter blade away from the rolls, said cutter blade being manually movable about its hinge axis to contact a selected roll.

4. A device of the character disclosed comprising a normally vertical rack element inclusive of means for rotatably mounting a plurality of rolls of material thereon in vertically spaced relationship and having vertical undercut ways at opposite sides, slides positioned in said ways, a bar carried on the slides and positioned across the rack adjacent rolls thereon, a cutter blade hinged to said bar for conjoint sliding movement therewith to selected rolls, a spring on the bar positioned to urge the cutter blade away from rolls on the rack, said cutter blade being manually movable about its hinge axis against tension of the spring to contact a selected roll, a counterweight connected with the bar, and means on the rack for holding rolls mounted thereon against unwanted rotation.
